UNITED STATES PATENT OFFICE.

MILFORD G. CHANDLER, OF CHICAGO, ILLINOIS, ASSIGNOR, BY MESNE ASSIGNMENTS,
TO CURTIS B. CAMP, TRUSTEE, OF OAK PARK, ILLINOIS.

CARBURETOR.

Application filed June 28, 1920. Serial No. 392,152.

To all whom it may concern:

Be it known that I, MILFORD G. CHANDLER, a citizen of the United States, and resident of Chicago, in the county of Cook and State of Illinois, have invented a certain new and useful Improvement in Carburetors, of which the following is a full, clear, concise, and exact description, reference being had to the accompanying drawings, forming a part of this specification.

My invention relates to carburetors for internal combustion engines. The carburetor to which my invention is applied is arranged for lifting fuel from a low level supply tank to the float chamber of the carburetor by suction derived from the suction of the engine.

It is the object of this invention to provide a fuel lifting carburetor in which the air entrance to the mixing chamber is in a form simulating an expanding Venturi tube, the fuel nozzle being located so as to discharge in a position near the throat of this Venturi tube where the suction is always higher than that of the mixing chamber.

It is characteristic of the carburetor in which the fuel is fed to the induction passage by suction produced at a point of restriction in said passage rather than by some anterior throttling device such as an anterior air valve, that a greater proportion of fuel per volume of air will be delivered to the carburetor at high engine demands than at low engine demands unless some means is provided to overcome this characteristic. The characteristic above referred to is markedly present where the air is drawn into the carburetor through a fixed orifice. In carburetors in which the orifice enlarges, as it does in the present carburetor, and in which the fuel is fed at substantially the throat of this orifice, the characteristic above referred to, of the tendency to enrich at high demands, is ordinarily more than compensated for by the lack of increased velocity through the orifice due to its enlarged size at high engine demands. In the present carburetor, this overcompensation is again compensated for by so shaping the orifice that it more nearly simulates a Venturi tube when wide open than when it is in a more nearly closed position, resulting in a higher proportionate suction at the discharge end of the nozzle

for high engine demands than for low engine demands.

A further object of the invention is the provision of mechanism operable in response to slight changes in size of the main air inlet, which mechanism controls the suction on the surface of the fuel in the carburetor float chamber to regulate the fuel feeding differential between the float chamber suction and that which draws the fuel into the induction passage.

Other objects of the invention will be pointed out in the following detailed description of the apparatus.

My invention is illustrated in the accompanying drawing in which

Figure 1 is a vertical section through the intake passage of the carburetor.

Figure 2 is an elevation, with the float chamber removed.

Figure 3 is a section on the line 3—3 of Figure 1.

Figure 4 is a section on the line indicated by 4—4 in Figure 3.

Figure 5 is a perspective of one of the expanding shoes.

Figure 6 is a section through the vacuum Venturi tube and its housing, and

Figure 7 is a diagram showing the contours 7^a, 7^b and 7^c of the opening through the induction passage at the respective planes indicated at 7^a, 7^b and 7^c of Figure 3 when the shoes are in the position shown in Figure 4.

A flanged annulus 10 forms a portion of the induction passage enclosure and carries the throttle 11 controlled by an arm 12. Side walls 13 and 14 partially enclose the mixing chamber 15 and are joined at 17 by screws 18. The inner faces of these walls 13 and 14 are shaped to conform to the intersection of two surfaces of rotation constructed around the centers 20 and 21; the shape being such that the shoes 22 and 23 rotatably mounted upon the pivots 20 and 21, when moved to various angular positions about their pivot points, constitute substantial seals against leakage between the carburetor mixing chamber 15 and the spaces 25 and 26 behind the shoes. The angle of divergence between the side plates 13 and 14 is about 7½°, and the shoes 22 and 23 are formed so that their surfaces coming adjacent these side plates conform to such divergence as well as to the curvature 110

of the side plates, as clearly shown in Figures 3 and 5. The openings back of the shoes 22 and 23 are closed by means of plates 30 and 31.

In view of the deteriorating effect of gasoline on die cast metal, the float chamber 32 and nozzle support 33 are preferably made of brass and suitably attached to the halves 13 and 14 by screws 34 and 35. To facilitate drilling of passageways for fuel and suction as hereinafter more fully described, the float chamber casting is preferably made separate from the nozzle support and attached by means of the screws 36. The nozzle 38 is of venturi form and is so positioned that its discharge end 40 is located at the point of highest suction in the intake passage of the carburetor when the velocity of the air through the carburetor is at its highest. This nozzle Venturi tube is provided with a plurality of jet openings 41 located at a step of sudden enlargement in the passage through the Venturi tube, it having been found by experiment that the presence of a sudden enlargement considerably increases the suction efficiency of a Venturi tube into which fuel is being delivered at the Venturi throat. The Venturi tube 38 is threaded into the nozzle support 33 in a manner which provides a fuel passage 42 entirely surrounding the nozzle Venturi tube so that fuel is delivered substantially equally through all of the openings 41. The annular space 42 is connected by means of registering passageways 43 and 44 with the lower portion of the float chamber 32, the opening 41 being controlled by a needle valve 45. The nozzle support 33 is enlarged at 47 as shown in dotted lines, Figure 7, to conform to the curvature of the upper and lower shoes so that when the shoes are in their most contracted positions, they contact with the member 47 and substantially close the entrance into the mixing chamber, excepting through the nozzle Venturi tube 38 and through the vacuum Venturi tube 50. The vacuum Venturi tube 50 is supported in a projecting part 51 formed on the outside of the side plate 14. This Venturi tube connects with the mixing chamber through the passage 52 and has its throat connected by the passage 53 and registering passage 54 with the upper part of the float chamber. The rod 55 interposed across the passage 52 constitutes a restriction in said passage and is so shaped as to provide the varying restrictions as demanded to provide the proper differential between the float chamber vacuum and the mixing chamber vacuum to supply the right proportions of fuel at all engine speeds. The rod 55 is reciprocated by means of the rack 56 and pinions 57. These pinions are carried upon the extended ends of the pivot rods 20 and 21 and serve not only to reciprocate the rod

55 but at the same time to maintain the shoes 22 and 23 in corresponding positions. The shoes 22 and 23 are provided with openings 58 through which suction is communicated from the mixing chamber to the closed spaces 70 behind the shoes. Springs 59 are supported between the inner parts of the shoes and the cover plates 30 and 31 and are arranged for suitable adjustment by means of screws 60. Float chamber 32 is provided with the usual 75 float and a float control valve for maintaining a constant level of fuel. The float chamber cover effectively seals the upper part of the float chamber so that a depression may be maintained therein for lifting fuel from a 80 low level supply tank, this fuel being brought into the float chamber through the connection 61 in a manner well understood.

In the operation of this device, starting, for example, at low engine speed, the nozzle 85 Venturi tube 38 together with the vacuum Venturi tube 50 are so sized as to supply the necessary air for idling, while at the same time constituting such a restriction as to provide a depression or suction in the carburetor mixing chamber equivalent to about 90 18 inches of gasoline in a manometer tube. With this degree of suction in the mixing chamber, the vacuum Venturi tube 50, by its multiplying action, provides a dépression or suction of about 36 inches of gasoline in the upper spaces of the float chamber, this amount being sufficient to maintain a supply of fuel in the float chamber under the assumed conditions of operation. If a greater 95 float chamber suction is desired, a smaller opening for the nozzle Venturi tube must be provided so that that tube will constitute a greater restriction to the incoming air. When the throttle 11 is opened to something greater 100 than the engine idling position, the suction in the mixing chamber will tend to increase. This suction is communicated to the spaces behind the shoes, and tends to open the shoes against the tension of the springs 59 because 105 portions of the shoes extend outwardly from the point of contact of the shoes with the member 47 and those portions are exposed to atmospheric pressure. The springs 59, therefore, are so adjusted that with a very slight 110 increase in mixing chamber suction, the shoes start to open and thus admit air through the secondary air passage around the primary nozzle 38, and thus prevent the mixing chamber suction from increasing more 115 than just that amount necessary for creating a balance.

When the air enters the mixing chamber between the shoes 22 and 23 and the enlargement 47 surrounding the end of the nozzle 120 Venturi tube 38, a local increase in suction is created at a point indicated on the drawing by the numeral 65. From this point toward the throttle, the local suction gradually disappears until the mixing chamber 125 130

suction is reached at a point about three quarters of an inch nearer the throttle. As the throttle is opened still further and a still greater amount of air flows into the mixing chamber, the localized suction increases and the point of maximum local suction travels downstream until, with wide open throttle and full engine speed, the point of maximum local suction is substantially at the 10 discharge end of the nozzle Venturi tube in this device in which the size and shape of the intake passage change on increase of speed and throttle opening. It will be seen that the maximum local suction in the induction passage is substantially at the openings through the shoes 22 and 23 and is, therefore, communicated to the spaces behind the shoes. Thus, although the pressure of the springs 59 increases as the shoes 20 open, the localized suction also increases and this latter grows in almost the same proportion as the increase in spring pressure with the result that while a suction of 15 inches 25 of gasoline is maintained in the mixing chamber with the shoes in closed position, the shoes will be completely opened by a mixing chamber suction of not more than the equivalent of 25 inches of gasoline.

In the idling condition, the suction at the 30 discharge end of the nozzle Venturi tube 38 is substantially the same as the suction throughout the entire mixing chamber because the air current passing through the intake passage at idling speed is so slight 35 as to produce no appreciable suction, and the suction within the intake passage is practically the static suction but as the shoes 22 and 23 open, the shape of the passageway which they form in conjunction with the side walls 13 and 14 assumes more nearly the shape of a true Venturi tube so that when the shoes 22 and 23 are fully opened, not only is the maximum 40 suction in the mixing chamber obtained but also the maximum localized suction is at the same time obtained through the shape which the intake passage at that time assumes. As has been pointed out above, the suction at the discharge end of the nozzle 45 Venturi tube and in the mixing chamber under idling conditions is substantially the same, about fifteen inches of gasoline. At full speeds the suction in the mixing chamber increases to approximately twenty-five 50 inches of gasoline, while under such conditions the localized suction at the end of the nozzle Venturi tube is equivalent to about fifty inches of gasoline. It will thus be seen that in this device, by a change of mixing chamber suction from fifteen to twenty-five inches, the local suction at the end of the nozzle Venturi tube has changed from fifteen to fifty inches of gasoline.

The action of the nozzle Venturi tube itself upon the suction at the throat is pec-

uliar and quite difficult of understanding and analysis. An exploring tube inserted to a point opposite the jet openings in the nozzle Venturi tube discloses a suction at idling equivalent to about 37 inches of gasoline. The suction at the same point at full engine demand is equivalent to about 55 inches of gasoline, that is, with only that amount of gasoline passing through the jets necessary for running the motor at idling 70 speed, the multiplying effect of the nozzle Venturi tube 38 increases the suction from 15 inches at the discharge end to 37 inches at the throat, whereas under full engine demand the quantity of mixture passing 75 through the nozzle Venturi tube is only sufficient to enhance the suction from 50 inches of gasoline at the discharge end to 55 inches at the jets. At every engine demand, if the needle valve 45 is left in a constant position 80 there is a certain differential between float chamber suction and mixing chamber suction, which supplies the best mixture of fuel and air. In order that this best differential may be absolutely secured, the rod 55, which 85 is interposed as a restriction between the vacuum Venturi tube 50 and the mixing chamber, is shaped so as to variously obstruct the passage in order that the effectiveness of the vacuum Venturi tube 50 may 90 be regulated.

In a vacuum feed carburetor of the type here illustrated, the amount of suction available at the jets is the factor which limits the amount of suction which can be 100 maintained on the fuel in the float chamber. The present structure is such that at the highest engine demand the induction passage of the carburetor has an almost perfect venturi form with the discharge end 105 of the nozzle Venturi tube opening into the induction passage at the point of highest local suction therein. This results in a very high relative suction at the jet openings and thus permits of a high float chamber 110 suction for lifting fuel to the float chamber. At all lower speeds, and consequently at lower engine demands, something else than the most efficient shape is secured for the induction passage, but even so, the discharge 115 end of the nozzle Venturi tube is maintained at a point near the area of greatest local suction so that at all speeds other than the lowest speed, the discharge end of the nozzle Venturi tube is subjected to a local suction 120 considerably greater than the suction in the mixing chamber at a point where it is unenhanced by the venturi effect of the diverging walls of the induction passage.

It is well known that when the throttle 125 of an ordinary carburetor is suddenly opened so that there is a sudden inrush of air, some special provision must be made to prevent the mixture from becoming suddenly so lean that the engine will miss or 130

backfire. The present structure inherently provides an excess of fuel at the time of sudden inrushes of air due to the quick opening of the throttle because the suction, which is communicated to the mixing chamber by the quick opening of the throttle, first acts upon the inner faces of the shoes 22 and 23 drawing them toward one another and thus momentarily enhancing the suction in the mixing chamber and increasing the flow of fuel to the mixing chamber. This action of the shoes is due to the restriction interposed by the holes 58 which prevent the localized suction of the mixing chamber from being immediately communicated to the spaces behind the shoes. In other words, since it requires a little time for air to circulate through the openings 58 to bring up the suction behind the shoes 22 and 23, the suddenly increasing suction in the mixing chamber partially closes the shoes and consequently provides a momentarily increased flow of fuel through the jets. This action is also aided by the fact that the suction on top of the fuel in the float chamber is derived through a somewhat long and quite small passage from the throat of the vacuum Venturi tube 50 to the upper spaces of the float chamber which acts to prevent the suction on the top of the fuel in the float chamber from increasing materially at the time of the sudden increase in suction at the jets.

Although my invention is shown and described in reference to a specific embodiment, it is to be understood that certain modifications may be made from this embodiment without departing from the spirit or scope of my invention.

What I claim is:

- 40 1. In a carburetor the combination with an induction passage of a pair of movable shoes constituting opposite walls of said passage, a pair of closed chambers in which said shoes operate, and means affording a passageway between the induction passage and the spaces behind said shoes for creating a suction in said spaces for causing the movement of said shoes and means centrally located between the shoes to deliver fuel to the induction passage.
- 45 2. In a carburetor the combination with a body portion constituting a part of an induction passage of a Venturi tube constituting a fuel nozzle having its discharge end opening into said passage, a pair of movable shoes mounted in said body portion and adapted to close about the discharge end of said Venturi tube to restrict the induction passage, and means dependent upon the suction in the induction passage for moving said shoes about their supporting pivots to enlarge the restricted opening into said induction passage.
- 50 3. In a carburetor for raising fuel from a low-level supply tank to a chamber ap-

parturtenant to the carburetor, the combination with a fuel-feeding Venturi tube of a suction-producing Venturi tube having its discharge end opening into the induction passage of the carburetor and having a connection between its throat and the chamber pertinent to the carburetor for creating a suction therein for lifting fuel thereto, a pair of movable walls adapted to assume various positions dependent upon the quantity of air passing through said induction passage, and means movable under the influence of said movable walls for controlling the size of the passageway between said vacuum-producing Venturi tube and the induction passage of the carburetor.

4. In a carburetor for raising fuel from a low-level supply tank to a chamber appurtenant to the carburetor, the combination with a Venturi tube for creating suction in the chamber appurtenant to the carburetor for lifting fuel thereto, means for varying the opening into the induction passage of the carburetor and means for varying the opening between the suction-producing Venturi tube and the induction passage of the carburetor, said means being operatively connected together and a nozzle Venturi tube for delivering fuel from the chamber pertinent to the carburetor to the induction passage.

5. An expanding induction passage for carburetors comprising a pair of opposed shoes pivotally mounted so as to present faces forming diverging walls for said induction passage, said shoes when open forming with other walls of the induction chamber a passage having substantially a venturi shape when the shoes are swung to their wide open positions, and openings through said shoes for the creation of suction behind the shoes for causing the operation thereof and a nozzle Venturi tube located centrally between said shoes and discharging at a point of high suction in the induction passage.

6. An expanding induction passage for carburetors comprising a pair of opposed shoes pivotally mounted so as to present faces forming diverging walls for said induction passage, said shoes when open forming with other walls of the induction chamber a passage having substantially a venturi shape when the shoes are swung to their wide open positions, an opening through one of said shoes for creating suction behind said shoe for causing the operation thereof, a mechanical connection between said shoes causing them to operate in unison and a Venturi tube constituting a fuel nozzle located centrally in the induction passage and discharging into the same at a point of high suction therein.

7. In a carburetor the combination with a body portion constituting an induction

passage, a throttle in said body portion, a pair of shoes pivotally mounted in said body portion, and adapted to swing to vary the size and shape of the induction passage, a 5 nozzle member having its discharge end situated between said shoes, said shoes being formed so that the point of restriction created by them is near the discharge end of said nozzle, spring means for pressing 10 said shoes toward said nozzle, means communicating between enclosed spaces behind said shoes and the induction passage at a point near the discharge end of said nozzle, and a fuel supply chamber connected with 15 said nozzle.

8. In a carburetor the combination with an induction passage and a fuel chamber, a tube forming a small inlet into the induction passage, a connection from an intermediate point in said tube to the upper 20 space of the fuel chamber, means responsive to suction in the induction passage for controlling the size of the inlet to said induction passage which admits the bulk of the air thereto, means operatively connected 25 with the passage controlling means for varying the discharge orifice of said tube for

varying the degree of suction in the fuel chamber, and a nozzle for delivering fuel from said chamber to the induction passage. 30

9. In a carburetor the combination with an induction passage, of a float chamber, a vacuum producing Venturi tube extending from atmosphere into the induction passage and having its throat connected with the 35 upper space of said float chamber for producing a suction therein to lift fuel thereto, a nozzle Venturi tube also extending into said induction passage and having its throat connected with the lower part of said fuel chamber for extracting fuel therefrom and delivering the same to the induction passage, an automatic device for controlling the flow of secondary air into the induction passage, and means connected with said automatic device for controlling the flow of air through the vacuum Venturi tube for delicately 40 regulating the suction in the float chamber. 15

In witness whereof, I hereunto subscribe my name this 23rd day of June, 1920.

MILFORD G. CHANDLER.
